UNITED STATES PATENT OFFICE.

WARREN S. HILL, OF BOSTON, MASSACHUSETTS.

CASH AND PARCEL CARRYING SYSTEM.

SPECIFICATION forming part of Letters Patent No. 295,172, dated March 18, 1884.

Application filed February 6, 1884. (No model.)

To all whom it may concern:

Be it known that I, WARREN S. HILL, of Boston, in the county of Suffolk and State of Massachusetts, have invented a new and useful Improvement in Cash and Parcel Carrying Systems, which improvements are fully set forth in the following specification.

My improvement relates to a cash-carrying system wherein is employed a car running on a wire way, and has especial reference to the mechanism employed to stop and retain the car when it has reached the end of its run.

It consists of a buffer and a retaining device secured to the wire way, about which it is disposed axially, so that the wire passes through its center, and a hooked arm or lever pivoted to the car and held against a stop by a spring, by means of which it is kept in position to engage with the retaining-flange of the buffer, all of which will be more particularly described hereinafter.

Referring to the drawings, Figure 1 represents a side elevation, showing the different parts in position when the car has reached the end of its run and is secured to the buffer. Fig. 2 shows the hooked arm made integral with the handle for throwing the car along the wire, and the stop that keeps it in position to engage with the buffer. Fig. 3 is a longitudinal vertical section, showing the construction of the buffer, and its relation to the wire way and to the parts shown in Fig. 2. Fig. 4 shows another form in which the buffer may be made.

In the drawings, A represents a car, the grooved wheels of which, a^a , run on the wire B. C is the buffer, through which the wire B passes, and to which is secured the clamp c^c . The central piece of the frame, a' , has its ends extended beyond the uprights that carry the grooved wheels, and a projection on its upper side, a^2 , (see Fig. 2,) is grooved to bestride the wire B, and forms what may be termed a "buffer end," a^2 . As this is the part that strikes the projecting end of the buffer, a somewhat similar projection extending downward, a^3 , receives the pivoted arm D, the pivot being shown at d' . The hooked end d^2 is shaped so as to readily slide over the beveled edge of flange f' on the buffer when they come together. The arm D may be made integral with the handle d^2 , by which the car is

thrown along the wire. A projection, d , on the top of the arm D has a bearing on the frame a' , as shown at a^4 , against which it is held by a spring, g , thereby forming a stop, by means of which the arm D is held in position to engage with the flange f' of the buffer. The spring g is secured to the stop d and to the frame a' at a^4 . The buffer C is in two parts—one fixed and the other movable. The fixed part c has a lug, c' , at its outer end, and a strap, c^2 , is secured to it by two screws, only one of which, c^3 , is shown in the drawings. The wire B is clamped between the lug c' and the strap c^2 , thereby securing the buffer to the wire without danger of injury to the wire, as would be the case were a set-screw employed. The movable part of the buffer, f , is fitted to move on the extended cylindrical part of c . It has a flange, f' , which acts as a catch for the hooked arm D. A groove, f^2 , receives the pin c^4 , which limits the outward movement of f . A washer, f^3 , of leather or other material, may be fitted into a recess in the end of f , to lessen the noise when the parts come together. The buffer-spring h is placed between the flange c^5 of the fixed part c and the flange f' of the movable part, and when the car strikes the buffer its momentum is received by the spring h as the movable part f is pushed toward and onto the fixed part c , and the yielding of the spring brings the car to a gradual stop, the reaction of the spring bringing the parts again into their normal position.

The operation of my invention is thus described: As the car A comes toward the buffer C, the hooked arm D is, by means of the stop d^2 and the spring g , held in position so that the inclined surface of the hook d^2 strikes the beveled edge of the retaining-flange f' , and by the yielding of spring g slides over it, and the car and buffer become locked together at the instant of contact between the buffer end of the car, a^2 , and the projecting end of the buffer, f^3 , and both move forward together until the inertia of the car is overcome by the resistance of the buffer-spring h , when the recoil of the spring restores the parts to their normal position again. The car is propelled along the wire B by the handle d^2 , which is pivoted to the car by being made integral with the arm D, and a slight pressure on the handle in the

direction the car is to be sent releases the hook d^2 from the retaining-flange f' , and the car is easily thrown along the wire B.

Having thus fully described my invention, 5 what I claim as new, and desire to secure by Letters Patent, is—

1. In a cash and parcel carrying system, a car provided with a pivoted hooked arm held against a stop by a spring, and a buffer disposed axially on the wire way, consisting of a fixed part secured to the wire, and a yielding part moving against a spring, and having a retaining-flange to engage with the pivoted hooked arm, substantially as set forth.

15 2. In a buffer for a cash-carrying system, the combination of the fixed part c , with lug

c' , strap c^2 , screws c^3 , and pin c^4 , and the movable part f , with retaining-flange f' , slot f^2 , washer f^3 , and the spring h , substantially as shown and described.

20

3. In a cash-carrying car, the combination of the handle d^2 , made integral with the pivoted hooked arm D, the stop d , spring g , and frame a' , substantially as shown and described.

In testimony that I claim the foregoing as my 25 own invention I hereunto affix my signature in presence of two witnesses.

WARREN S. HILL.
